UNITED STATES PATENT OFFICE.

LOUIS TAMIS, OF NEW YORK, N. Y., ASSIGNOR TO SCHANFEIN & TAMIS, OF NEW YORK, N. Y., A FIRM COMPOSED OF BERNARD SCHANFEIN AND LOUIS TAMIS, ALSO OF NEW YORK, N. Y.

VANITY CASE.

Application filed October 27, 1924. Serial No. 746,001.

To all whom it may concern:

Be it known that I, LOUIS TAMIS, a citizen of the United States, and a resident of New York, borough of Manhattan, in the county of New York and State of New York, have made and invented certain new and useful Improvements in Vanity Cases, of which the following is a specification.

My invention relates to a vanity case and 10 has for its object to provide a case which is particularly adapted for the present style of ladies' hair dressing, in that it combines in a novel manner a mirror and a convenient size of comb.

15 A further object is to provide a vanity case so constructed and arranged as to receive and house a comb therein and especially adapted to prevent breakage or damage to the comb as it is being inserted within 20 or withdrawn from the housing.

25 A further object is to provide a vanity case of pleasing appearance and with a portion of one edge of the case cut away, and to provide in combination therewith a comb, the top of which is made similar to the edge of the case and when the comb is in place the top will exactly fill the cutaway portion of the edge, so that a neat and pleasing appearance will be provided.

30 A further object is to provide a novel form of lock for holding the comb in place, and, with the comb so positioned, the handle of the comb will protrude beyond the side wall of the case and provide a convenient 35 hook whereby the case may be secured to a chain or other suitable support.

With the foregoing and other objects in view, my invention consists in the improved 40 vanity case illustrated in the accompanying drawing and hereinafter described and claimed, and in such variations and modifications thereof as will be obvious to those skilled in the art to which my invention relates, it being understood that changes may 45 be made within the scope of what is claimed without departing from the spirit thereof.

The preferred embodiment of my invention is disclosed in the accompanying drawing, wherein:

50 Figure 1 is a front plan view of my improved vanity case, the mirror being removed so as to illustrate the details of construction of the case and the comb being

illustrated in dotted lines in a partially removed position;

55 Figure 2 is a view in section taken on the line 2—2 of Figure 1, with the mirror in place and the comb removed;

Figure 3 is a top plan view of the case; 60 Figure 4 is a plan view of the comb with its attached handle; and

Figure 5 is a detail view in section of the comb and adjacent parts of the case in which the comb is positioned.

Referring specifically to the several views, 65 wherein similar reference numerals designate corresponding parts throughout, the casing 10 is composed of the back wall 11 and the side walls 12. The back and side walls are preferably formed of some precious metal, such as gold, and are suitably engraved so as to present a neat and pleasing appearance. The front wall 13 is formed by the mirror 14 which is mounted in a suitable frame 15 which fits within and is 70 rigidly secured by the side walls 12, the side walls being preferably inclined or V-shape, as more clearly illustrated in Figure 2.

75 One of the side walls is cut away at its center as illustrated at 16, which renders the interior of the case between the front and rear walls accessible for the housing or storage of the comb 17, as illustrated in dotted lines in Figure 1 and in full lines in 80 Figure 4. The distance between the inner surfaces of the front and rear walls of the case is just sufficient to nicely contain the comb 17 therebetween. In order to prevent

any danger of breakage of the comb during 85 insertion within or withdrawal from the casing, I provide two spacing springs 18, these being preferably secured at their ends by the sockets 19, the latter being soldered or otherwise permanently secured at the corners of the casing. The spacing springs 18 project from the four corners of the casing and at their center portions extend parallel 90

so as to bear against the comb and thus hold it against any side play and at the same time 95 are adapted to hold the comb in alignment and prevent it from tilting either to one side or the other as it passes through the opening 16. Immediately adjacent the cutaway portion or opening 16, I provide a small 100

105 housing 20, the side walls of which form

a continuation of the edges of the opening 16 and thus prevent the teeth of the comb from catching or becoming broken as the comb is inserted within or withdrawn from the case.

At the upper extremity of the comb I provide the member 21 which is so shaped and designed as to form a continuation of the side wall of the case, and which member 21 has a handle 22 projecting thereabove. In order to lock the comb in position within the case, a suitable snap fastener 23 is provided, the upper extremity 24 projecting up within the handle and providing means whereby the snap fastener may be released. The snap fastener is further characterized by the pawl or dog 25 which is adapted to fit within the notch 26 within the back wall of the casing and thus lock the comb in place.

With the parts as thus arranged, the handle 22 is not only adapted to serve for withdrawing the comb from the casing, but, in addition, forms a convenient means whereby the vanity case may be carried upon a

chain or may be secured to other form of support. Further, the handle provides a convenient place for the gripping of the comb while being used.

Having thus described and explained my invention, I claim and desire to secure by Letters Patent:

A vanity case comprising a receptacle having an opening at one end, a comb adapted to pass through the opening, and inwardly bowed springs located interiorly of the receptacle and disposed one at each end of the opening and adapted to receive the comb between them, the end portions of the springs being confined at the corner portions of the receptacle.

Signed at New York, borough of Manhattan, in the county of New York and State of New York, this 24th day of Sept., A. D. 1924.

LOUIS TAMIS.
